PACK FOR CARTRIDGES OR THE LIKE

Dudley H. Smith, Waterville, Maine

Application March 31, 1958, Serial No. 50,247

Term of patent 14 years

(Cl. D58—13)

Fig. 1 is a top plan view of a pack for cartridges or the like embodying the present invention;

Fig. 2 is a side view of the pack of Fig. 1; and

Fig. 3 is a view, partly in section and partly in elevation of the pack of Fig. 1.

What is claimed:

The ornamental design for a pack for cartridges or the like, as shown.
